UNITED STATES PATENT OFFICE.

WILHELM BENICKE AND HEINRICH WESTERBECK, OF HANOVER,
GERMANY.

LINE-SPACING DEVICE.

SPECIFICATION forming part of Letters Patent No. 779,063, dated January 3, 1905.

Application filed May 9, 1904. Serial No. 207,073.

To all whom it may concern:

Be it known that we, WILHELM BENICKE and HEINRICH WESTERBECK, subjects of the German Emperor, and residents of Hanover, Germany, have invented certain new and useful Improvements in Line-Spacing Devices, of which the following is a specification.

This invention relates to a device whereby the cylinder of a type-writing machine may 10 be rotated round its axis for any required amount and that by closing an electric contact.

In the annexed drawings, given by way of example, Figure I represents a vertical section on Q R of Figs. III, IV, V, Fig. II being a horizontal section on S T of Figs. III, IV, V; Fig. III, a cross-section on U V of Figs. I and II. Fig. IV is a cross-section on W X of Figs. I, II. Fig. V is a cross-section on Y Z of Figs. I, II.

20 The cylinder proper comprises the hollow cylinder-body A, in which the solenoid B is fixed. Inside the hollow cylinder-body A and at one end of the solenoid B are fixed the two guide-rails C C', while at the other end 25 of the solenoid B is placed the short hollow cylinder D, fixed to the frame F by means of a nut E. Upon the inner wall of the hollow cylinder D are arranged two helicoidal guides G G', Figs. I, II, III. The soft-iron core H, 30 forming a part of the solenoid B and extended by a brass piece I, is guided by the cross-piece K, sliding upon the two guide-pieces C C'. The free end of the brass piece I carries the disk L, furnished with balls, which run 35 in the egg-shaped grooves of the disk, Fig. IV. The guide-piece N, which is guided upon the helicoidal slides G G', is pressed by a nut M against the balls of the disk L in such a way that they can still turn. One end of the 40 winding on the solenoid B is connected to the brush P, bearing upon the ring O, while the other end is electrically connected to the cylinder-body A.

If now by closing a contact an electric current is sent into the solenoid B by the spring-brush P and the ring O, the soft-iron core H is drawn into the solenoid B, and consequently the guide-piece N also slides upon the guides G G'. Being arranged in a helix, the balls are

50 pivoted back by the movement of the guide-piece N into the reduced extremities of the hollows in the disk L and cause the coupling between the guide-piece N and the disk L, and as the hollow cylinder D is fitted to the frame F the core H and the brass piece must partake 55 of the rotation and move by the guide-piece K the cylinder A proper. When the current is interrupted, the spring Q pushes back the core; but during this period the roller A remains at rest, because the balls again run in the 60 largest part of the hollows. The angle to be rotated by the roller A each time the circuit is closed is regulated by the pin R, which is pushed into the hollow cylinder A and where it is rendered immovable by the screw S. This 65 pin limits the stroke or distance traversed by the soft-iron core H and the piece I of brass.

Having now fully described our invention, what we claim, and desire to secure by Letters Patent, is—

1. The combination with a hollow paper-receiving roller or cylinder of a type-writer, of a solenoid arranged therein, and having a 70 slideable core, guide-ribs secured to the inner wall of the cylinder and parallel to the axis of the latter and upon which guide-ribs the said core is slidably mounted at one end, a hollow cylinder fixedly arranged within the first-mentioned cylinder and provided with helicoidal 75 guides on its inner wall, a guide-piece adapted to travel upon the said helicoidal guides, coupling means interposed between said guide-pieces and the core and adapted to permit of the free revolution of the core when no electric current is passing through the solenoid 80 but to rigidly connect the core and guide-piece when an electric current is passing through the solenoid and a spring arranged to act upon the core to return it to normal position when no current is passing through the 85 solenoid.

2. The combination with a hollow paper-receiving roller or cylinder of a type-writer, of a solenoid arranged therein, and having a slideable core, guide-ribs secured to the inner wall 90 of the cylinder and parallel to the axis of the latter and upon which guide-ribs the said core is slidably mounted at one end, a hollow cyl-

- inder fixedly arranged within the first-mentioned cylinder and provided with helicoidal guides on its inner wall, a guide-piece adapted to travel upon the said helicoidal guides, coupling means interposed between said guide-pieces and the core and adapted to permit of the free revolution of the core when no electric current is passing through the solenoid but to rigidly connect the core and guide-piece when an electric current is passing through the solenoid, a spring arranged to act upon the core to return it to normal position when no current is passing through the solenoid, and means for regulating the extent of movement of the core and consequently the degree of rotation of the paper-receiving roller.
3. The combination with a hollow paper-receiving roller or cylinder of a type-writer, of a solenoid arranged therein, and having a slideable core, guide-ribs secured to the inner wall of the cylinder and parallel to the axis of the latter and upon which guide-ribs the said core is slidably mounted at one end, a hollow cylinder fixedly arranged within the first-mentioned cylinder and provided with helicoidal guides on its inner wall, a guide-piece adapted to travel upon the said helicoidal guides, coupling means interposed between said guide-pieces and the core and adapted to permit of the free revolution of the core when no electric current is passing through the solenoid but to rigidly connect the core and guide-piece when an electric current is passing through

the solenoid, a spring arranged to act upon the core to return it to normal position when no current is passing through the solenoid, and a pin projecting within the said paper-receiving roller and bearing upon one end of the core, said pin being adjustable for the purpose specified.

4. The combination with a hollow paper-receiving roller or cylinder of a type-writer, of a solenoid arranged therein, a slideable core therefor, said core having a soft-iron section and a brass section united together, guide-ribs secured to the inner wall of the cylinder and parallel to the axis of the latter and upon which guide-ribs the soft-iron section of the core is slidably mounted at its outer end, a hollow cylinder fixedly arranged within the first-mentioned cylinder and provided with helicoidal guides on the inner wall, a guide-piece adapted to travel upon said helicoidal guides, a ball-track in the outer end of the brass section of the core, balls interposed between said brass section and the said guide-piece and running in said track, and a spring acting upon the core to return it to normal position when an electric current is not passing through the solenoid.

In testimony whereof we have hereunto set our hands in presence of two witnesses.

WILHELM BENICKE.
HEINRICH WESTERBECK.
